UNITED STATES PATENT OFFICE.

ALBERT P. GOLDMAN, OF CHILlicothe, ILLINOIS.

CAR-COUPLING.

960,538.

Specification of Letters Patent. Patented June 7, 1910.

Application filed December 12, 1908. Serial No. 467,299.

To all whom it may concern:

Be it known that I, ALBERT P. GOLDMAN, a citizen of the United States of America, residing at Chillicothe, in the county of 5 Peoria and State of Illinois, have invented certain new and useful Improvements in Car-Couplers, of which the following is a specification.

My invention relates to certain new and 10 useful improvements in car couplers and has for its object the construction and combination of parts in form and substance to cause the draft to be thrown upon the main body parts of the car coupler and to relieve the 15 pivot pin between the knuckle and the head from strain; to provide a perfectly closed head at the top to prevent the entrance of foreign substances; to provide a lock set for the coupler pin whereby it may be lodged 20 and held without the operator being required to maintain hold upon the operating lever and to provide means for operating the coupler parts either from the side or top of the car, and other details of novelty in 25 combination which are hereinafter fully set forth.

That my invention may be more fully understood, reference is had to the accompanying drawings, in which—

30 Figure 1 is a front elevation of my coupling showing its connection with a car body; Fig. 1^A is also a front elevation of my device showing a modified form of connection for operating the coupling parts. Fig. 2 is a top plan view shown in connection with the body of a car; Fig. 3 is a perspective view showing the knuckle and arm connection; Fig. 4 is a front elevation showing portions broken away and also showing in solid and dotted 35 lines two positions of adjustment of parts of the coupler. Fig. 5 is a vertical section through the center of the coupler taken from the left hand side of the same; Fig. 6 is also a vertical sectional view taken from the 40 right hand side of the coupler; Fig. 7 is a detail perspective view of an ear portion of the coupler head; Fig. 8 is a detail perspective view of the coupler pin or block; Fig. 9 is a detail perspective view of a bar designed 45 to connect the coupler pin or block with the mechanism for shifting the block or pin; and, Fig. 10 is a detail perspective view of a modified form of lever designed for use in connection with the shifting parts of the

coupler. Fig. 11 is a perspective view of 55 the knuckle showing parts broken away.

In these drawings, A represents the draw bar provided with a coupler head A' and is suitably recessed as shown, to receive certain working parts and within said recess are 60 provided the shoulders a a, see Fig. 5, also one of the shoulders appearing in Fig. 4.

The knuckle B is pivoted to ears projecting from the draw head as shown, by means of the pin B² and is adapted to be forced 65 open by an actuating spring when free to move, which said actuating spring B³ shown in Fig. 7 is coiled around the pivot pin B², one end of the same being carried within a recess B⁴ and the other end carried within 70 the slot B⁵, the arm of the spring which bears in slot B⁵ bearing somewhat above the face of the ear portion B⁶ of the upper head and is adapted to engage the recess B⁷ within the hub portion of the knuckle (such 75 recessed portion being shown in Fig. 11) so as to produce tension on the knuckle as it is closed. The knuckle proper is provided with the elongated portion C, being that portion below the curvature shown in 80 Fig. 3 and is provided with the flange or lug projection C² which flange or lug projection is provided as a stop to prevent the coacting corresponding parts from slipping past each other while coupled by reason of 85 unevenness in the height of cars or irregularity in the road bed and also to prevent dropping out and falling upon the ground of the coupler. It will readily be seen that the coacting parts or couplers being secured 90 together and locked, that if one of them should be pulled out from the body of the car it cannot slip out but rests upon the ledge C².

Integral with the knuckle is the arm D 95 projecting substantially at right angles with the face thereof and is provided with the shoulders as d, as shown in Fig. 3, there being a corresponding shoulder on the lower face of the arm in identically the same relative location. This arm as will be understood, is adapted to extend within the cavity in the draw head and when the knuckle is closed, the shoulders d on the said arm will engage the shoulders a in the draw head and the said shoulder engagements will sustain 100 the draft or pull between the cars thereby relieving the pin from strain.

To lock the knuckle in closed position, I have provided the block or pin E which is housed in the casing E' as best shown in Fig. 4, which is made in the form of the block, the shape of the same being best shown in Fig. 8. The block E is adapted to move up and down in the inclosing case or pocket for the purpose of alternately releasing or engaging the arm D of the knuckle.

F is a bar adapted to be carried within the channel F' formed in the body of the draw head. The channel may be best seen by reference to Fig. 6. The bar is provided with the finger projection F² which is adapted to engage with the opening E² in block E. The lower end of the bar depends from an opening in the bottom of the draw head and is suitably pivoted to the arm G, which arm is also pivoted to the draw head as at I. The direct connection between the bar F and the arm G is by the arcuate slot J which facilitates the coaction of the two arms so that as arm G is raised into the position shown in dotted lines by the operator drawing outwardly upon the rod K, the bar F will be elevated into the position shown in dotted lines carrying with it the block E and in such movement the connecting pin g between the two arms will move rearwardly in the slot.

In the operation of the parts, it is desired that when the locking block is raised, to disengage the arm D of the knuckle, that it may be sustained in such elevated position without the operator being required to maintain his hold upon the rod K or other means that may be provided to manipulate the parts referred to.

To accomplish the above specified object, the bar F is provided with the laterally extending shoulder f which is channeled out as at m and there is also provided the tapered projection n at the forward end of the shoulder inclining rearwardly to the lower portion of the channel, also there is provided the notch i in the bar just above the lug f which is of sufficient size to embrace the lower wall A⁴ of the draw head. By the formation of the bar as above specified, as the bar is elevated and as it approaches the maximum limit of such elevation, the rounded portion or elbow e will engage the tapered projection n at its maximum forward part and as the elbow passes upwardly and to the bottom of the channel N, the bar F will be forced forwardly so as to cause the notch i to engage the wall A⁴ at the edge of the opening through which the bar passes, thereby causing the said bar to be seated thereon so as to hold the block in its elevated position. The lock set position thereby obtained makes it possible for the lifting bars of the respective couplers of a train to be moved to this lock set position,

thereby unlocking the couplers so that cars may be withdrawn from the train without requiring the operator to uncouple each particular car desired to be detached therefrom.

In the operation of the device, the parts having been assembled with the locking block elevated and the knuckle opened, the same being automatically so opened through the action of the spring B³, the coacting coupler in the same opened condition by contact, will cause the arm D to be pushed rearwardly and in being so pushed rearwardly, the forward end D² thereof will, on account of the relative arrangement of the arm D with the bar F strike the inner face of said reach, pushing it rearwardly a sufficient distance for it to clear the edge of wall A⁴ of the draw head, this disengagement of the said bar from the lock set position being accomplished just as the arm D has reached the point in its movement into the recess within the draw head that accomplishes the proper engagement of the coacting knuckles for the proper coupling of the parts together and just at this point, the locking block E will by force of gravity drop downwardly and in front of the face D³ of the arm D, thereby locking the parts together.

I close the top of the draw head completely to prevent foreign substances from becoming lodged within the coupler head which, if permitted to do so, would destroy the efficiency of the coupler. By means of forming the coupler head in the manner herein shown and free from all upward projections from the upper face of the head, I am able to use this coupler in connection with passenger coaches, which is a feature of advantage.

In connection with Fig. 1, I have shown a modified form of connection for operating the locking block, the same being shown in dotted lines and consists of a lever M shown in Fig. 10 which is pivoted to the draw head as at O and also to the bar F as at S and the chain T is provided for operating the same. An elongated slot V is provided in lever M at its pivotal connection with the draw head, which permits sufficient play to enable the bar to be shifted to and drawn from its proper lock set position. In the use of this character of connection for shifting the locking block, it is designed to be applied where it is desirable to operate the coupler to be locked and unlocked from a point above the same, as for instance, where the coupling connection must lead to a switch engine or to the top of a car.

It is obvious that my invention may be embodied in different form from that shown herein, without departing from the spirit of my invention.

Having thus fully described my invention,

what I claim and desire to secure by Letters Patent, is:

1. In a car coupler and in combination with the swinging knuckle thereof having an elongated depending portion provided with a laterally extending lug at its lower end and provided with a knuckle tail having vertically disposed lateral flanges thereon, a head recessed to receive the knuckle tail and provided with flanges adapted to engage the flanges on the knuckle tail, a coupler pin vertically movable and a bar vertically movable to raise the pin and laterally movable to facilitate its being lodged in a lock set position when the pin is disengaged from the knuckle tail, substantially as described. 70
2. In a coupler and in combination with the swinging knuckle, and its tail, a housing having a vertical opening therein, a vertically movable pin contained within said housing, a bar supported upon the coupler head for raising the pin to disengage the knuckle tail and to move the pin into a lock set position, the said bar having a laterally projecting grooved member with an inclined stop at its lower end and recessed above the projection to provide a lock set seat, substantially as described. 75
3. In a car coupler, a locking pin and means for operating said locking pin from its lower end, said means comprising a vertically disposed bar having a loose connection with the pin and being formed with a recess therein to provide a lock seat, a slotted swingable arm engageable through its slot with the vertically disposed bar and operable to raise the bar and to lodge it upon a support to hold the pin in lock set position, and means connected with said swingable part and extending to the side of the car adapted to operate said arm, substantially as described. 80
4. In a coupler, a locking head having a vertical recess therein, a vertically operating locking pin located within said recess, an arm pivoted to the head and provided with an arcuate slot, a bar connected at one end with the pin and at the other with the arcuate slot of the arm, said bar being provided with a grooved lateral projection terminating with an inclined stop at its outer end and also provided with a lock seat, the said bar being adapted to be moved with the swinging of the arm vertically and laterally to cause the pin to release the coupler from the knuckle tail and to lodge the pin in the lock set position and means extending to the side of the car for operating said arm, substantially as described. 85
5. In a coupler, the combination with a swinging knuckle and a head, the latter being provided with a recess or opening therein having its lower end open, of a vertically operating locking pin working in said opening, an arm pivoted to the head and provided with an arcuate slot and with a lobed portion upon its upper edge, a bar vertically movable in an opening in the head and connected at its upper end with the locking pin and at the lower end in a sliding engagement with the arcuate slot of the arm, said bar being provided with a cut away portion to provide a lock seat and with a laterally extending part grooved in its lower face and terminating with an inclined stop at its outer extremity, and means for operating the arm, whereby as the arm is swung upwardly, the lobed portion thereof will engage the lower face of the lateral projection of the bar, causing said bar to be raised, and with it the locking pin, and when said pin reaches its maximum raised position, the lobed portion of the arm contacting with the inclined stop on the laterally projecting part will shift the bar laterally and cause the locking seat therein to be lodged upon a ledge or support on the head and when the swingable arm is moved in the opposite direction, the locking pin will be released, all substantially as described. 90
6. The combination with a draw head having a laterally swinging knuckle and a vertically slideable coupler pin adapted to hold the knuckle closed when the pin is lowered, of an arm pivoted to the head and provided with an arcuate slot therein and with a lobed portion thereon, a bar having a loose connection with the pin and the arm, the same being provided with a locking seat therein, means connected with the pivoted arm to operate it, whereby the bar, connected with the locking pin, may be moved vertically to release the knuckle tail and shifted laterally to a lock set position, substantially as described. 95
7. In a car coupler of the class described, the combination with a coupler head provided with an opening in the body thereof, the horizontally disposed inner walls of said opening being formed with shoulder portions, a coupling knuckle pivotally mounted therein, the tail portion thereof provided with lug portions upon its upper and lower faces adapted to engage the shoulders in the head when the knuckle is closed, a vertically arranged and movable locking pin for locking and holding the coupling knuckle in closed position, a bar having a loose connection with the pin and provided with a locking seat therein and a stop thereon, an arm pivoted to the head and movable vertically below the locking pin and provided with an arcuate slot therein adapted to be connected with the lower end of the bar in a slideable relation therewith and a part thereon adapted to engage the stop on the bar to shift it laterally and means connected with the pivoted arm to move it vertically whereby the bar connected with the locking pin may be moved vertically to release the knuckle tail 100
- 105
- 110
- 115
- 120
- 125
- 130

and shifted laterally to lock set position, substantially as described.

8. In a car coupler of the class described, the combination with a coupler head provided with an opening in the body thereof, the horizontally disposed inner walls of said opening being formed with shoulder portions, a coupling knuckle pivotally mounted therein, the tail portion thereof provided with lug portions upon its upper and lower faces adapted to engage the shoulders in the head when the knuckle is closed, a vertically arranged and movable locking pin for locking and holding the coupling knuckle in closed position, means for raising the pin comprising an arm pivoted to the head and provided with an arcuate slot therein and a lobed portion on the upper face thereof, a bar having a loose connection at its upper end with the pin and loosely connected at its lower end with the arcuate slot of the arm, said bar being provided with a locking seat and with a grooved lateral projection

terminating with an inclined stop at its outer end and a rod connected with the movable end of said arm and extending to the side of the car, whereby when the rod is drawn outwardly the arm will be raised the lobed portion thereof engaging the lateral projection on the bar and causing the same to be raised and with it the locking pin; the engaged portion of the bar with the arcuate slot in the arm moving laterally in said slot until the lobed portion of the arm strikes the inclined stop on said projection when the bar will be moved to engage its lock seat with the ledge on the head, thereby placing the locking pin in lock set position, substantially as described.

In testimony whereof I have affixed my signature in presence of two witnesses.

ALBERT P. GOLDMAN.
